FREDERIC W. HILLARD, OF PRINCE BAY, STATEN ISLAND, NEW YORK, ASSIGNOR TO
MARY R. HILLARD, OF MIDDLEBURY, CONNECTICUT

TYPEWRITING MACHINE

Application filed March 14, 1929. Serial No. 346,898.

The invention herein relates to certain new and useful improvements in typewriting machines. It is in many respects an improvement over the machine of my Patent No. 1,296,957, patented March 11th, 1919. Comparing the machine of said patent with my herein improved machine. Both machines are front strike typewriters. In both the carriage comprises a truck and a platen carriage, operatively connected for endwise movement together crosswise the machine in letter spacing. In both machines the platen carriage is locked down, throughout the line of typewriting, against being lifted up out of its normal writing position. In both machines, also, means are provided for unlocking the carriage and lifting it up, after it has first been moved out of its normal writing position. But the means for so doing differ in the two machines and the results are different. In the machine of the patent, as shown and described therein, the platen carriage cannot be moved rearward bodily, out of the printing field. It can only be moved out of the printing field, by moving it to a non-writing position beyond one end of the line of typewriting,—as say to a predetermined point slightly preceding and before the beginning of the line of typewriting. At said point means are provided for unlocking the carriage and lifting it up. But in my herein present machine means are provided for moving the platen carriage rearward bodily, out of its writing position and out of the printing field, at any point in the line of typewriting; and for then unlocking it and then lifting it up. Therefore, while, in the patent, the platen carriage can only be lifted up at a predetermined point; in my herein machine the platen carriage can be lifted up at any point in the line.

In a front strike typewriter it is advantageous, for many reasons, to be able to unlock the platen carriage and swing it up rearwardly into an elevated position. But it is inconvenient to always have to move it back endwise, beyond the beginning of the line of typewriting, as in the patent, to unlock it so that it can be lifted up. Hence, I have devised means, in my present machine, for

unlocking the platen carriage and swinging it up into its elevated position at any point in the line of typewriting.

Comparing briefly, the carriage lift mechanisms of the two machines. In the patent it is as follows: The platen carriage is simply hinged to the truck, thus providing for only one movement between those two parts; namely one to swing the carriage up and down on the truck, after it has been unlocked. In order to unlock the carriage to lift it up, the front rail, which locks the carriage down in writing position, is notched or cut away at a predetermined point,—slightly preceding and before the beginning of the line of typewriting. The notch enables the locking finger at the front of the carriage (that underlies the front rail to lock the carriage down), to escape up through the cut away notch and unlock the carriage so that it can be lifted up at said predetermined point.

In my herein machine the carriage lift mechanism is as follows: The platen carriage is linked to the truck and is hinged to the links, thus providing for two separate and succeeding movements between the said two parts (i. e., between the platen carriage and the truck). The two movements are:

First: The links which connect the platen carriage to the truck, provide the means for a rearward bodily movement of the carriage, out of its writing position and out of the printing field, at any point in the line of typewriting. Such rearward movement clears the carriage from the parts that normally lie close in front and also brings it into a position such that it is released from the means that lock it down when in writing position.

Second: After said rearward, separating and releasing movement of the platen carriage, the hinge joint between the links and the carriage provides the means for swinging the carriage up, to lift it up into its elevated position, at any point in the line; and co-operates with means to lock the carriage back bodily, in its rearward position, out of the printing field; and also with means to lock the carriage up in its elevated position, at any point in the line of typewriting.

It is the combination of the two means,

namely the one for moving the platen carriage rearward bodily, and the other for lifting it up from its rearward position, that enables me to lift up the carriage into its elevated position at any point in the line, in my herein machine.

It is obvious that my herein means for lifting the platen carriage up into its elevated position at any point in the line, is applicable to typewriters which shift to upper case and lower case printing positions, as well as to those that print in a single case only. In many typewriting machines, as for instance the Underwood typewriter, the platen carriage is shiftable to upper and lower case printing positions. In other machines, as say in the well known L. C. Smith typewriter, the carriage is non-shiftable and the type bar segment is shiftable to upper and lower case printing positions. I contemplate preferably applying my herein carriage to a machine wherein the type bar segment shifts for lower case and upper case writing.

In my carriage, as shown herein, there is a truck at the rear and a platen carriage at the front and a linked connection between the truck and the platen carriage. The truck is mounted, for endwise movement only, in ball bearing raceways, and the platen carriage frame is linked to the truck for endwise movement of the platen carriage with the truck and also for crosswise movement of the platen carriage on the links, toward and away from the truck, for purpose which I will now set forth.

In my herein machine the carriage can be raised to a lifted position at any part of the line of print. This is accomplished by first moving the platen carriage rearwardly relatively to the truck, and then lifting it and locking it up on the truck in its rearward position. Such rearward movement of the platen carriage enables me to employ a sound muffling glass or otherwise transparent casing which covers the front and the top of the machine back to the platen when the platen is in printing position. By moving the carriage rearwardly on the truck I am enabled to raise it to lifted position thereon without interference with the sound muffling casing.

In addition to my glass or otherwise transparent casing above mentioned, I enclose the whole body of the machine as far as possible with casings so as to muffle and confine the sounds within the machine. In this way I secure a very quiet and practically noiseless typewriter.

Aside from my above described sound muffling casing, and even if such casing be not employed, there is still great advantage in my present machine over that of my said Patent, No. 1,296,957, in that in my present machine I can lift the platen carriage at any point in its line of travel crosswise the machine and without danger of interferences with the rib-

bon mechanism, paper scales or other devices on the platen carriage or frame of the typewriter, and without providing guards to avoid such interferences. It is obviously of great advantage to be able to lift up and lower the platen carriage on the truck at any point in the line of travel, irrespective of the use of a sound muffling casing.

In the accompanying drawings which form a part of the specification:

Fig. 1 is a plan view of so much of the carriage and parts of the typewriter as are necessary to show my herein invention. In this view the platen carriage is in writing position.

Fig. 2 is a side view of the same with the carriage in writing position.

Fig. 3 is a view similar to Fig. 2 excepting that the carriage is in its lifted and locked back position.

Figs. 4 and 5 are detail views of parts of the mechanism for locking the carriage in its lifted position and for unlocking it to lower the carriage. Fig. 4 shows the normal position of the parts, when the carriage is in writing position. Fig. 5 shows the position of the parts when the carriage is lifted and locked up. Figs. 4 and 5 are taken on line A—A Fig. 1.

Fig. 6 is a perspective view of the left hand trunnion (looking from the front of the machine), and of the left hand carriage link and the left hand pivotal connection between the link and the trunnion.

Fig. 7 is a corresponding view of the right hand trunnion, its carriage link and the right hand pivotal connection between the trunnion and the link. In Fig. 7 there is also shown journaled in the upper end of the right hand link the rod which supports the platen carriage at the rear and on which the carriage swings to its lifted position on the truck.

Only the right hand end of the platen carriage support rod is shown in Fig. 7, but in the assembled machine the right hand trunnion (Fig. 7) and the left hand trunnion (Fig. 6), line up with each other at the front of the truck; and the right hand end of the carriage support rod is journaled in the upper end of the right hand carriage link (Fig. 7) and the left hand end of said rod is journaled in the upper end of the left hand carriage link (Fig. 6).

1 shows the machine frame. 2 is the truck. The truck is mounted in the race-ways 3 and 4 on the bearing balls 5. The truck is substantially similar to that in my said Patent 1,296,957 and therefore needs no further description. At each end of the truck are mounted the trunnions 6. Pivotally mounted at their lower ends on the trunnions 6, at either side of the machine, are the carriage links 33. The links are pivoted on the trunnions by the shafts 21, and in the upper ends

of the links is journalled the platen carriage pivot rod 18. This rod extends crosswise the machine, from the one side to the other, and is journalled in the upper ends of both the carriage links 33. The plate 8 of the frame of the platen carriage 7 is rigidly fastened to shaft 18, so that the platen carriage and the shaft 18 turn together in the lifting movement of the carriage on the truck, to the position shown in Fig. 3. The frame of the carriage 7 comprises the plate 8 at the rear and the two side bars 9 and 10 integral therewith. There is no front rail to the platen carriage. The side bars 9 and 10 are bound together by the rod 11 which extends across the carriage underneath the platen. The paper feed rolls 12 are mounted on cross rod 11 as usual in the Underwood typewriter. Depending from the cross rod 11 midway between the side bars is a dependent lug 13 on which the carriage ball bearing support wheel 14 is pivotally mounted. A retaining piece 15 is clamped between the screw 16 and the pivot post of the roller 14. The roller rides on the way rod 17. It will be seen in Fig. 2 that the rear edge of the periphery of roller 14 rides on the way rod 17 and that the retaining piece 15 is close to the way rod when the platen carriage is in its normal writing position. As stated the platen carriage is rigidly fixed to pivot rod 18 so that the rod turns with the carriage when the latter is lifted. It will be seen that when the platen is in normal writing position the retaining piece 15 prevents the lifting of the carriage.

When the carriage is in its writing position, it cannot be swung up to lift the platen into its elevated position, for two reasons: first, because, as above stated, the retaining piece 15 prevents such movement; and second, because the rearwardly extending arms 43 and their offset and overhanging lugs 44, also prevent such lifting movement. I will discuss this second means.

The frame of the platen carriage, 7, is provided, at the rear, with the carriage plate 8, integral with the frame or rigidly fixed thereon; and, integral with the carriage plate, 8, are the two upwardly extending lugs 42 and their rearwardly extending arms 43. At the rear ends of the two arms, 43, are the respective two offset lugs, 44, the lug on the right hand arm being offset right handedly and the one on the left hand arm, offset left handedly. The right handed lug 44 overlies the upper plane surface of the trunnion 6, on the right hand end of the truck, 3; and the left handed lug overlies the similar plane surface on the trunnion, 6, at the left hand end of the truck. Both of the trunnions, 6, are rigidly fixed on the truck.

The platen, 41, and the portion of the platen carriage frame that holds the platen, are in front of the carriage pivot rod, 18, on

which the platen swings up to its elevated position; while the arms 43 and their offset, overlying lugs, 44, are in the rear of said pivot rod. Therefore, in order to swing up the platen, on the pivot rod, 18, into its elevated position, the arms, 43, and their overlying lugs, 44, must be swung downwardly, because they are on the opposite side of the pivot rod, 18. But since the lugs, 44, overlie the upper plane surfaces, 45, of the trunnions, 6, and the trunnions are rigidly fixed on the truck, 3, and cannot swing down, it follows that the arms 43 and their lugs 44 cannot be swung down. Hence the arms, 43, and their lugs, 44, prevent the lifting up of the platen and platen carriage into their elevated positions, so long as they remain in their normal writing positions. Thus the retaining piece 15 and the offset, overlying lugs, 44, are the joint means for locking down the platen and the platen carriage in their normal writing positions; but they leave them free to be moved endwise across the machine, as in letter spacing. The escapement rack 19 is mounted on the side arms 20 which in turn are mounted on the short pivot rods 21, one on each trunnion. The escapement release lever 22 is pivotally mounted on screw 23 on the frame of the carriage 7 and, at its rear end, on the inner side a projection 24 is provided. The forward end of the side arms 20 are provided on their outer sides, with similar projections 25 in line with the projections 24 of the escapement release levers. When the carriage is in normal writing position the projection 24 underlies projection 25 so that when the release lever is depressed the rack will be lifted up and disengaged from the escapement wheel pinion 26.

Springs 27 at the inner end of the pivot rods 21 tend to hold the escapement rack downwardly in the normal position at all times. This is the well known construction of the Underwood typewriter and needs no further description.

Fig. 3 shows the lifted position of the platen carriage and the dotted line positions of certain of the parts show their positions when the carriage has been moved back but before it is lifted. The spring 28 and stop pin 29 holds the release lever 22 in its normal position. The dotted line position shows that in the backward movement of the carriage, the support roller 14 has been brought to a position such that the front edge of the roller is in line with and resting on the carriage way rod 17 and that the retaining piece 15 has been moved rearwardly far enough so that the carriage can be swung on the pivot rod 18 into its lifted position, without interference by the retaining piece and that projection 24 on the release levers has been moved free of projection 25 on the rack arms.

Referring to Figs. 1 and 2 it will be seen

that the sound muffling glass casing 30 is close up to the platen when the latter is in normal writing position, and that the rearward edge 30a of the casing extends over the platen, so that the lifting of the carriage 7 would then be obstructed by said casing. But when the carriage has been moved back it is moved away from the glass case so that it is free to be lifted without interference with the casing. The rearward movement of the platen carriage 7 also clears it of the ribbon mechanism and all interfering parts so that it can be lifted at any point in its line of travel.

I will now describe the means for lifting and locking up the carriage. I provide a toggle joint 31 at each side of the machine at the rear of the platen carriage. The rear end of the rear member of each toggle joint is pivotally mounted on the trunnion 6 on the pivot screw 32. The forward member of the toggle joint is mounted on the outer ends of the pivot rod 18. The pivot rod 18 is carried in the upper ends of links 33. The links are pivotally mounted on the pivot rods 21 at their lower ends. The toggle joints are held in their normal positions by the release keys 34, (one only of which is shown in the drawing) toggle springs 35 and the adjustable stop pins 36 in the side frames of the carriage. The toggle joint release keys are keyed to the ends of cross rod 37. The screws 38 serve to hold the keys 34 (one only shown in the drawing) in their positions on the cross rod 37. By this means the cross rod 37 is caused to revolve whenever the toggle joint release key is depressed. Only one toggle joint release key 34 is shown in the drawing but there is preferably such a key at each side of the machine.

In Fig. 1 of the drawings the toggle joint release key, 34, is shown at the right hand end of the platen carriage, with its key lever keyed onto the right hand end of the pivot rod 37, that extends across the platen carriage, and held thereon by its screw 38, with the rear end of the key lever underlying the middle joint of the right hand toggle joint, 31, adapted to buckle up the toggle joint whenever the key 34 is depressed. A keyless toggle joint release lever is also shown in Fig. 1, on the left hand end of the platen carriage, similarly keyed onto the left hand end of the pivot rod, 37, and held thereon by its screw, 38, with the rear end of the lever underlying the middle joint of the left hand toggle joint, 31. The rear ends of the two toggle joint release levers, the one on the right hand and the other on the left hand end of the pivot rod, 37, are similar to each other and they are both rocked upward together on the pivot shaft 37, to buckle up their respective toggle joints whenever the release key, 34, is depressed. As above stated, the two said toggle joint release levers 65 may each be provided with a release key, as

34. This for convenience of operation and for adjustment purpose, at both ends of the platen carriage.

At its rear end each toggle joint release lever engages the middle joint of its toggle joint, 31, so that when the key, 34, is depressed the toggle joints, 31, 31, will be moved from the straight line positions shown in Figs. 1 and 2 to the buckled up positions shown in Fig. 3. Such buckling up actuation of the two toggle joints, 31, 31, results in moving the pivot rod 18 rearwardly and therefore moves the carriage 7 rearwardly from the position shown in Fig. 2 to that shown in Fig. 3.

It has been shown above, that the platen carriage, 7, is normally locked down in its writing position by two means, namely by the retaining piece 15, close back of the way rod 17, and by the right hand and left hand offset, overlying lugs 44, 44, resting close above the plane surfaces, 45, 45, on the tops of the two trunnions 6, 6. The platen carriage is also normally restrained forward or locked forward in its writing position. This is effected by the two toggle joints, 31, 31, the one at the right hand end of the platen carriage and the other at the left hand end. The two toggle joints are normally in the substantially straight line positions shown in Figs. 1 and 2. They are brought into such positions by the tension springs, 35, and their exact adjusted positions are determined by the adjustment of the eccentric stop pins, 36, and the toggle joint release levers that underlie the middle joints of the two toggle joints, respectively.

Each of the toggle joint release levers should, preferably, be provided with an adjustable stop pin, 36. This because it is the two toggle joints, 31, that bring the carriage pivot rod, 18, into its proper normal position at both ends of the pivot rod; and said pivot rod, when properly adjusted, brings the platen carriage, 7, into its proper position in the printing field, with both ends of the platen, 41, in the printing plane. Hence the two toggle joints, 31, 31, both require proper adjustment into their correct straight line positions, preferably by means of two toggle joint levers, two toggle springs, 35, and two adjustable stop pins, 36.

The platen carriage, 7, is restrained forward, or locked forward, in its normal writing position, because of the two toggle joints, 31, which hold it there securely. Since the toggle joints are normally in their straight line adjusted positions, they prevent a blow on the front of the platen, as in typewriting, from driving the platen rearwardly, out of the work field. The buckling up of the two toggle joints, 31, by the toggle joint release key, 34, releases the platen carriage from its restrained forward, or locked forward, posi-

tion, in the work field, and moves it into its rearward position, ready to be lifted up.

The terms printing field and work field are used interchangeably herein, and the term printing plane has a closely related significance, as also has the term writing position.

The spring 39 tensioned by the adjustable collar 40 on shaft 37 tends to always hold the release key in lifted position against stop pin 36 and to lift it after it has been depressed. Thus the actuation of the toggle joint by the release key, in the construction shown, is the means for moving the platen carriage rearwardly, clear of the usual inking ribbon and ribbon holding and actuating devices, and for clearing the path of the retaining piece 15 from the way rod 17 when the carriage 7 is being lifted, and for moving the projection 24 on the release lever free of the projection 25 on the rack arm, so that the rack 19 will remain in engagement with the escapement pinion 26 and the truck and platen carriage will remain under control of the escapement and the usual main spring when the carriage is lifted.

Also in case the machine be provided with the sound muffling glass casing 30, the platen 41 will be, by the actuation of the toggle joint, moved rearwardly and away from said casing; so that the carriage can be lifted without interference of the platen with the casing.

It will be observed that in the normal writing position of the carriage, Fig. 2, the rear edge of supporting roller 14 rides on the way rod 17, while in the pushed back position of the carriage, Fig. 3, the front edge of the roller rests on the rail. The roller 14 is made wide enough so that the way rod will continue to support the carriage, even when the carriage is moved back ready to be lifted. While the carriage is being moved back and the retaining piece is moving away from the way rod 17 the carriage is still locked against being lifted until it has been moved fully back to the position of Fig. 3, by means I will now describe.

The carriage plate 8 is provided with upwardly extending lugs 42 at each side of the machine and arms 43 extend rearwardly and have offset parts 44 at their rear ends, the one being right handed and the other left handed, which lie over a plane surface 45 at the top of each trunnion 6. When the carriage is moved to its rearward position the offset parts 44 move rearwardly beyond the plane surfaces 45 of the trunnions so that the carriage can then swing upwardly. The trunnion is provided with a concave portion at 6a so that when the carriage is moved to its rearward position arms 42 and the hubs at the top of the link 33 will not collide with the trunnions. When the carriage 7 is so swung up the offset parts 44 swing downwardly into annular grooves 46 on the trunnions at each

side of the machine. At the end of their downward movement the parts 44 come against the stop pins 47. This limits and determines the fully lifted position of the carriage 7. As soon as the carriage begins to be lifted, the offset fingers 44 pass into the angular grooves 46 which are concentric with the carriage pivot shaft 18. Therefore the carriage is held in its rearward position during the whole of its upward movement and while it is in lifted position.

I will now describe the mechanism for locking the carriage 7 in its lifted position and also the means for unlocking the carriage to lower it from such position. Midway the length of the truck 2 a slotted piece 48 is fastened thereto and extends forward and carries the locking latch 49 and the camming dog 50, both pivoted side by side on pin 51 (see Figs. 1, 4 and 5). Pin 51 is a driven fit in the locking latch so that it rotates therewith, while the camming dog 50 is a running fit on said pin. The normal rearward position of the locking latch 49 is controlled by the eccentric adjusting screw 52, in slotted piece 48. The latch is normally held back against the screw 52 by tension spring 53.

The camming dog 50 is provided with a dog pin 54, driven therein, which projects back of the locking latch 49 and the flat spring 55 secured to piece 48 by screw 56, forces the pin 54 against the rear edge of the locking latch. The latch spring 53 is stronger than dog spring 55 so that the locking latch normally impinges upon the stop screw 52. The locking arm 57 is keyed on the carriage pivot shaft 18, so that its overhanging lug 58 is in line with the locking latch 49.

When the carriage is moved out of its normal writing position into its retracted position the locking arm 57 is moved from the full line position to the dotted line position in Fig. 4. When the retracted carriage is swung about pivot shaft 18 to raise the carriage to its lifted position the arm 57 is thereby swung downwardly to the position shown in Fig. 5. The locking latch 49 is provided with a camming face 59 eccentric to the carriage pivot shaft 18, and the locking arm 57 is provided at its far end with the overhanging lug or offset portion 58, in line with the locking latch camming face 59. As will be seen from the dotted line position of the locking arm 57 in Fig. 4 (i. e. the position of the arm after the carriage has been moved backward but before it has been lifted), the inner surface of the overhanging lug 58, as it swings downward while the carriage is being lifted, will engage camming face 59 on the locking latch and cam the latch forwardly away from stop pin 52. When the carriage has been fully lifted the upper edge of the offset lug 58 will have passed below the camming face of the latch lock, into the latch. Thereupon the locking latch spring 53 will again snap the locking

latch 49 rearwardly against the stop pin 52 thereby locking up the carriage.

Keyed or otherwise rigidly mounted on shaft 37 is the unlocking arm 60. The arm is to the right of the camming dog 50 (Fig. 1) but is provided with unlocking pin 61. Such pin is rigidly secured in the free end of unlocking arm 60 and is in line with the camming plate 62 on the right hand side of the camming dog 50. The dog pin 61, while it extends to the left in line with the camming plate 62, does not extend far enough to engage the main body of the camming dog 50 and hence is clear of the locking latch 49 also, since the locking latch is to the left of the camming dog.

The carriage is moved rearwardly by depression of the toggle joint release key 34 and since the release key 34 is keyed to the shaft 37, and the unlocking arm 60 is also keyed to the same shaft it follows that when the toggle joint release key is depressed the free end of the unlocking arm 60 will be moved into the dotted line position 60a (Fig. 4). In case the toggle joint release key 34 is released and lifted before the carriage is lifted then the arm 60 will simply move from the position 60a to the position 60b in Fig. 4. If the release key 34 be held depressed until the carriage has been lifted then the arm 60 will assume the position 60c in Fig. 5. When the release key 34 is released the arm 60 will swing down to the full line position in Fig. 5 while the release key is being returned to its normal lifted position. In passing from the dotted line position to the full line position in Fig. 5 the unlocking pin 61 will engage the front face of camming plate 62 on the camming dog 50 and cam the dog rearwardly from the full line positions of the dog pin 54 and camming plate 62, to the rear dotted line positions 54a and 62a. As soon as the pin 61 has passed below the cam plate 62 the camming dog 50, under the influence of its spring 55, will spring back to its normal position with the dog pin 54 against the locking latch, as shown in the full lines in Fig. 5.

It will thus be seen that if the toggle joint release key 34 is held depressed until the carriage has been lifted the arm 60 will not pass from the dotted line position 60c to the full line position Fig. 5 until after the carriage has been lifted; but if the release key 34 be released after the carriage has been moved to its rearward position and before being lifted then the camming dog 50 will be cammed rearwardly during the lifting of the carriage. But in either event when the carriage is lifted and the release key 34 is also released and lifted the unlocking arm 60 and its dog pin 61 will be in the full line position shown in Fig. 5, with the carriage locked up.

When it is desired to unlock the carriage in order to lower it, the release key 34 is de-

pressed, and the arm 60 is thereby caused to swing upwardly from the full line position of Fig. 5 to the dotted line position of 60c. In that movement the dog pin 61 engages with the under side of the cam plate 62 and cams the camming dog forwardly from the full line position of dog pin 54 and cam plate 62 to the forward dotted line positions 54b and 62b. But since the dog pin 54 impinges on the rear edge of the locking latch 49 it can only swing forward to the dotted line position 54b and 62b by also swinging the locking latch forwardly away from its stop screw 52, against the impulse of the spring 53, to the position 49a (Fig. 5). Hence when the carriage is in the lifted position and the release key 34 is depressed the locking latch is drawn forwardly far enough to release the offset lug 58 of locking arm 57 from the latch. The carriage is thus unlocked and free to be swung down to its normal level, into its rearward position. As the carriage is swung down, the rearwardly extending arms 43 (see Figs. 1, 2 and 3) swing upwardly, the offset lugs 44 moving upwardly in the grooves 46, and when the carriage roller 14 has come to its engagement with way rod 17, the lugs 44 will be above and free of grooves 46. The carriage will then be moved forward by the impulse springs 35 of the toggle joints, and the platen will thus be brought back to its normal writing position. As soon as the carriage begins to be moved forward the offset lugs 44 slide forward over the plane surfaces 45 on trunnions 6, thus locking the carriage against lifting movement at all times save only when the carriage is in its rear position with lugs 44 in line with annular grooves 46.

Thus the carriage cannot be lifted until it has been withdrawn rearwardly from its operative position far enough to avoid all interferences in the lifting movement, and after it has been lifted it has to be swung down again to its normal level with the carriage roller 14 resting on the way rod 17 before it can be moved forward again to its normal writing position. Hence it is obvious that the carriage can be lifted at any point in the line of travel without any danger of interferences with any of the parts in the machine during the lifting movement and during the return lowering movement. Not only am I thus enabled to lift the carriage at any point in the line without interference between the ribbon or ribbon mechanism and the paper guide rolls, etc., but I am also thereby enabled to employ a sound deadening casing covering the top and inclosing the exposed portions in front of the platen, and I can still easily and conveniently make erasures on the paper and manipulate the work sheets in any way without any interference with the sound inclosing casing. In Fig. 3 I show a sectional view of the sound muffling casing, 30, show-

ing how it comes over the top of the ribbon spools and over the printing point at the platen. In Fig. 1 the casing 30 is broken away over the type bar guide. The type bar 5 guide and other parts beneath the glass casing can, of course, be seen through the casing. I have broken away the casing 30 in Fig. 1 so as to more clearly illustrate that the casing at 30a reaches over and beyond the printing point at the platen so as to confine the sound, and that for this reason and any other interferences it is clear that the carriage could not be raised without first moving it rearwardly far enough for clearance 10 purposes. So far as I know such rearward movement of the carriage for such purpose is novel and I claim it accordingly.

In my present machine there is no front rail across the carriage in front of the platen. 20 Therefore, when the carriage is lifted nothing is in the way of erasing or of moving the work sheets, both original and carbon copies, forward from the platen.

The trunnions 6 are fastened to the truck 25 by screws 63. The trunnions reach forward and at their lower front ends are provided with hubs 64 to take in the short pivot rods 21, which latter can turn in the hubs but are rigidly fastened to escapement arms 20 to 30 turn therewith. The pivot rod 21 on the right hand side of the machine (Figs. 1, 2 and 7) is provided at its inner end with the head 65, and on the body of shaft, between the head 65 and the inner edge of trunnion 6, the spring 27 is coiled about the shaft, the inner 35 end being bent and inserted in the head and the outer end bent and inserted on the inner edge of the trunnion 6, and tensioned so as to hold the rod 21 and rack 19 down in engagement with the escapement pinion 26 when the carriage is lifted. The escapement pinion is connected with the escapement wheel 66 which latter is controlled by the usual dogs, not shown. The usual main 40 spring, not shown, is connected to the carriage by the usual main spring band 67 (see Fig. 3). In this way when the carriage is lifted and locked up, it will still be under control of the escapement.

55 Each pivot rod 21 has a bearing at the inner and outer sides in the forwardly extending hubs 64. The trunnions are slotted vertically between said bearings and the carriage links 33 are fitted into said slots and are pivotally mounted on the rods 21. At their upper ends the links 33 are provided with hubs and are pivotally mounted on the shaft 18, between the forward bearings of the toggle joints 31 and the arms 42, which latter extend up from carriage plate 8. Shaft 18 is rigidly fastened in the arms 42, to turn 60 with the carriage when the carriage is lifted.

65 It will thus be seen that the links 33 are the means for linking the platen carriage to the truck; that the toggle joints 31 are the

means for normally holding the links 33 in position to hold the carriage in its forward writing position; that the toggle joint keys 34, preferably one on each side of the carriage, are the means for actuating the toggle joints to swing the links 33 and the platen carriage rearwardly, relatively to the truck, before the lifting of the carriage; that the wide carriage supporting roller 14 is the means for supporting the carriage on way rod 17, in all positions, before the carriage is lifted; that the retaining piece 15 prevents the lifting of the carriage when in writing position; that the offset lugs 44 of arms 43 on the carriage plate 8, overlying the flat surfaces 45 of the trunnions 6, prevent the lifting of the carriage until it has been pulled back on the links 33 to its rearmost position; that, when the carriage is in its rearmost position, the offset lugs 44 enter the concentric annular grooves 46 in the trunnions and permit the lifting of the carriage but hold it in its rearmost position so long as the lugs 44 are in the annular grooves; that as the carriage is swung up the overhanging lug 58 80 on the locking arm 57 cams locking latch 49 forward by means of the camming face 59 until the lug 58 has moved fully below the camming face 59; that then the locking latch is snapped back into its normal position by its spring 53, thus locking the carriage up; that when it is desired to release the carriage to lower it, the depression of the key 34 rotates shaft 37 and thus swings the unlocking arm 60 upwardly so that its unlocking pin 61 85 engages the camming plate 62 and swings dog 50 forwardly, the latter by means of its unlocking pin 54 also swinging the locking latch 49 forward and thus releasing the locking arm lug 58 from the latch. Then the carriage 90 is free to be swung down until carriage support roller 14 engages way rod 17 and the carriage will be moved forward by links 33 to 95 normal writing position under the influence of the toggle joints 31 and their impulse 100 springs 35.

In Fig. 2 I show the locking arm 57 and its overhanging lug 58 which are mounted on shaft 18, and also unlocking arm 60 and unlocking pin 61 thereon, which are mounted on shaft 37. The remainder of the parts for locking up the carriage and for unlocking it from its lifted position are only shown in Figs. 1, 4 and 5.

In front strike visible writing machines, 120 of the type I show, the type bar segment is vertically arranged and either the type bar segment or the platen is shifted vertically for writing upper case characters. I move my carriage rearward bodily before lifting it, in 125 a direction at about right angles to the said shifting movements, moving it beyond the point of interference when lifting the carriage. I believe that it is broadly novel to thus move the platen carriage rearward bod- 130

ily out of the printing field for the purpose of lifting the carriage and I therefore so claim it. I also believe the combination of a carriage comprising a truck and platen carriage operatively connected for endwise movement together, in letter spacing, and wherein the platen carriage is movable, separately, rearward bodily in the machine, and also wherein means are provided to swing the platen carriage up, from its said rearward position, into an elevated position on the truck, is novel and I claim it accordingly.

I have shown my preferred means for linking the platen carriage to the truck for the purposes of my invention. Any other well known devices for linking or otherwise connecting the carriage to the truck, for movement rearwardly and forwardly in the machine, may be substituted without departing from the broad invention of moving the platen carriage back out of the printing plane in order to lift it at any point of the line without interferences. Owing to the forward and back transverse shifting movements of the platen carriage for lifting, it tends to simplicity to employ a carriage which does not also shift transversely to upper and lower case printing positions as shown herein, and to shift the type bar segment and type bars up and down for upper and lower case printing. But my invention is not limited to such structure. The platen carriage may be shifted up and down for upper and lower case printing, and also moved rearward transversely for shifting the platen out of the work field in order to lift it at any point in the line of print, as well as for computing operation without typewriting.

By the terms front strike typewriter and front strike visible typewriting machine, as used herein and the words visible writing front strike typewriter in the accompanying claims, I mean to include all machines in which the writing is done on the side of the platen facing the operator, whether on the horizontal plane of the platen or on the upper front quarter thereof.

While my herein machine is an improved standard office typewriter of the general type of that of my machine of said Patent No. 1,296,957, it is also well adapted for use as a computing, billing and bookkeeping typewriting machine, particularly in collating business forms, index cards, etc., as discussed in my pending patent application Sr. No. 336,506, filed January 31, 1929. When the platen herein is in its elevated position on the truck, the printing line is nearly at the top of the platen, and hence the collated matter will be in such position on the platen that it will have little tendency to slip out of collated position prior to the clamping of the forms or cards to the platen.

The machine of said patent also lifts the platen carriage up into an elevated position;

such that, when the carriage is lifted up, the printing line is nearly at the top of the platen. Hence, in that respect, the machine of the patent is equally adapted as is my herein machine, for collating business forms, index cards, etc.; but the machine of the patent has a carriage front rail that is very detrimental in assembling and collating business forms, etc., on the platen.

In the patent, the front rail extends across the carriage, in front of the platen, when the carriage is down in its normal writing position. Hence, when the carriage is lifted up, the front rail will be above the printing line and obviously will interfere seriously, with the assembling and collating of business forms, etc., on the lifted up platen.

My herein present machine is much better adapted, in that respect and in other ways, for combined typewriting and computing operations. Some of the reasons for this, are the following:

First: Because, in my present machine, there is no front rail across the platen carriage, in front of the platen. Hence collated business forms, index cards, etc., can be freely, easily and quickly assembled and collated at the printing line on the top of the lifted up platen, without hindrance from an interfering front rail interposed above the uplifted platen, as in the patent.

Second: Because, in my present machine, the platen carriage can be lifted and locked up at any point in the line. This is not true of the machine of the patent, but is highly important in computing, billing and book-keeping.

Third: Because, in my present machine, the platen carriage can be moved rearwardly, back out of the printing field and locked back in its rearward position, so that computing without typewriting can be done thereon. This is impossible in the machine of the patent.

Fourth: Because, in my present machine, the truck and the platen carriage are under escapement control and can be letter space fed endwise together, while the carriage is locked back in its lifted up position, out of the printing field. This also is necessary to enable computing without typewriting. In the machine of the patent, on the contrary, the truck and the platen carriage are not under escapement control and cannot be fed endwise while the carriage is lifted up; and computing without typewriting is impossible thereon.

Various changes in construction and arrangement of the parts may be made without departing from the spirit of my invention and some of the improvements may be employed without others, and I therefore wish it to be understood that I do not limit the invention to the precise details shown.

But I wish it understood that, regardless of

the precise details of construction and arrangement, a very important feature of my herein invention is, broadly speaking, the combination of means, as above enumerated, that enables me to release the platen carriage from its locked down and restrained forward writing position and to lift it up into its elevated position in the machine, at any point in the line of typewriting. Also that the means for moving the platen carriage rearwardly in the machine and locking it back, out of the printing field, and for then moving it endwise with the track under escape-
ment control, in letter spacing, as above 15 enumerated, is an important feature of my invention. This last is especially true in cases where computing operation without typewriting is required.

Having thus described my invention, what 20 I claim as new, and desire to secure by Letters Patent, is:

1. In a visible writing front strike type-
writer the combination of an endwise mov-
able truck, a platen carriage mounted for-
wardly of the truck and operatively con-
nected therewith, means for mounting the 25 carriage for movement out of the work field
toward the truck and means for mounting
the carriage to lift it to an elevated position
on the truck at the end of said movement to-
ward the truck.

2. In a visible writing front strike type-
writer the combination of an endwise mov-
able truck, a platen carriage mounted for-
wardly of the truck and operatively con-
nected therewith, means for mounting the 35 carriage for movement out of the work field
rearwardly toward the truck, a stationary
way rod to support the carriage and a sup-
porting roller mounted on the carriage and
resting on the way rod, said roller being 40 of such width that it supports the carriage
on the way rod both when the carriage is in
its forward writing position and also at the
limit of its rearward movement toward the
truck.

3. In a visible writing front strike type-
writer the combination of an endwise mov-
able truck, a platen carriage connected with 50 the truck and movable endwise therewith,
means for mounting the carriage to move
it rearwardly out of the work field trans-
versely of the truck, means for preventing
the lifting of the carriage until the end of its 55 said rearward transverse movement, and
means for mounting the carriage to lift it on
the truck at the end of said rearward trans-
verse movement.

4. In a visible writing front strike type-
writer, the combination of a truck movable 60 endwise, a platen carriage operatively con-
nected with the truck for endwise movement
therewith and also for a transverse movement
relatively to the truck, means for so moving

the carriage transversely including a key on
the carriage for so moving the carriage.

5. In a visible writing front strike type-
writer, the combination of a truck movable
endwise, a platen carriage linked to the truck
for movement therewith and also for a trans-
verse movement on the links toward and
away from the truck, toggle joints for vi-
brating the links to move the carriage trans-
versely and a key on the carriage to actuate
the toggle joints. 75

6. In a visible writing front strike type-
writer the combination of an endwise mov-
able truck, a platen carriage linked to the
truck for endwise movement therewith,
means for moving the carriage on the links
out of the work field transversely toward the
truck, means for preventing the lifting of
the carriage until the end of said transverse
movement, means for lifting the carriage on
the truck at the end of said transverse move-
ment, means for locking the carriage against
transverse movement while it is being lifted,
means for limiting the lifting movement of
the carriage and for locking it in its lifted
position on the truck. 80

7. In a visible writing front strike type-
writer the combination of a platen carriage,
a truck at the rear to form a travelling sup-
port for the carriage, an operative connection
between the truck and the carriage, comprising
links pivoted at their lower ends to the 95
truck and at their upper ends to the car-
riage, whereby the carriage may be piv-
otally swung first rearwardly toward the
truck and then upwardly on the truck, means
for locking the carriage in its elevated posi-
tion on the truck and a release key on the
carriage for unlocking the carriage from its
elevated position. 100

8. In a visible writing front strike type-
writer the combination of an endwise mov-
able truck, a platen carriage having an op-
erative connection therewith for endwise
movement, a transparent sound deadening
casing mounted on the machine and enclos-
ing the top of the typewriter forward of
the platen and reaching over the platen above
the printing point when the platen is in its
writing position, means for moving the car-
riage rearwardly away from said casing, and
means for swinging the carriage upwardly
from said last mentioned position to an ele-
vated one on the truck. 115

9. In a visible writing front strike type-
writer the combination of an endwise mov-
able truck, a platen carriage having an op-
erative connection therewith for endwise
movement, a transparent sound deadening
casing mounted on the machine and enclos-
ing the top of the typewriter forward of the
platen and reaching over to the platen above
the printing point when the platen is in its
writing position, means for moving the
platen carriage rearwardly away from the 120
125
130

said casing, means for swinging the carriage upwardly on said connection from said last mentioned position to an elevated position and means for locking the carriage to the truck in its said elevated position.

3 10. In a visible writing front strike type-
writer the combination of an endwise mov-
able truck, a platen carriage mounted for-
wardly of the truck and having a linked con-
nection therewith for endwise movement, a
10 transparent sound deadening casing mounted
on the machine and enclosing the typewriter
forward of the platen and reaching over to
the platen above the printing point when
the platen is in its writing position, means
15 for moving the platen carriage on its linked
connection toward the truck and away from
the said casing, means for swinging the car-
riage upwardly on said linked connection
20 from said last mentioned position to an ele-
vated position, means for locking the car-
riage to the truck in its said elevated position
and a release key on the carriage for unlock-
ing the carriage from its elevated position.

25 11. In a front strike typewriter the combination of an endwise movable truck, a platen carriage, means for operatively connecting the carriage with the truck for endwise movement therewith, said means including
30 means for mounting the carriage for bodily movement, relatively to the truck, rearwardly in the typewriter and also including means for lifting the carriage up on the truck into an elevated position thereon, after its
35 said rearward movement.

30 12. In a front strike typewriter the combination of an endwise movable truck, a platen carriage, means for operatively connecting the carriage with the truck for endwise movement therewith, propelling power for moving the truck and carriage endwise together, an escapement operatively connected with the truck to control the endwise movement of the truck and the carriage in 40 writing position, in the printing field, said means for connecting the carriage with the truck including means for mounting the carriage for bodily movement rearwardly in the typewriter, out of the printing field, and also 45 including means for lifting the carriage up on the truck into an elevated position thereon, after its said rearward movement, the truck and the carriage remaining under control of the escapement when the carriage is in its 50 55 said writing position and also when it is in its said elevated position out of the printing field.

13. In a front strike typewriter the combination of a platen carriage, a truck which forms a travelling support for the carriage, a linked connection between the truck and the carriage, whereby the carriage moves endwise with the truck in the printing field and whereby it can be moved rearward bodily on the typewriter, out of the printing field, a

pivotal bearing in said connection whereby the carriage can be swung up into an elevated position on the truck, after its said rearward movement, and means for locking the carriage up in its said elevated position out of the printing field. 70

14. In a front strike typewriter the combination of an endwise movable truck, a platen carriage, a linked connection between the truck and the carriage for endwise movement of the carriage with the truck in writing position in the printing field, means for locking the carriage in said writing position, means for moving the carriage rearward bodily on said linked connection, to move it out of the printing field and to unlock it, and means for re-locking the carriage in said rearward position out of the printing field. 75 80

15. In a front strike typewriter the combination of an endwise movable truck, a platen carriage, a linked connection between the truck and the carriage for endwise movement of the carriage with the truck in writing position in the printing field, means for locking the carriage in said writing position, means for moving the carriage rearward bodily on said linked connection, to move it out of the printing field and to unlock it, means for re-locking the carriage in said rearward position, a pivoted bearing in said connection whereby the carriage can be swung up into an elevated position on the truck, while in its said re-locked rearward position and means for locking the carriage up in its elevated position out of the printing field. 85 90 95 100

16. In a front strike typewriter the combination of an endwise movable truck, a platen platen carriage, a linked connection between the truck and the carriage for endwise movement of the carriage with the truck in writing position in the printing field, means for locking the carriage in said writing position, propelling power for moving the truck and carriage endwise together, an escapement operatively connected with the truck to control the endwise movement of the truck and the carriage in writing position, means for moving the carriage rearward bodily on said linked connection, to move it out of the printing field and to unlock it, and means for re-locking the carriage in said rearward position, the truck and the carriage remaining under control of the escapement when the carriage is in its re-locked rearward position out of the printing field.

17. In a front strike typewriter the combination of an endwise movable truck, a platen carriage operatively connected with the truck for endwise movement therewith in its writing position in the printing field, means for mounting the carriage for rearward transverse movement out of the printing field, a stationary way rod to support the carriage, a supporting roller mounted on the carriage and resting on the way rod, said roller being 130

of such width that it supports the carriage on the way rod when the carriage is in its writing position and also throughout its said rearward transverse movement out of the 5 printing field.

18. In a front strike typewriter the combination of a truck movable endwise, a platen carriage linked to the truck for endwise movement therewith and also for a transverse 10 movement on the links rearwardly and forwardly on the typewriter, toggle joints for vibrating the links to so move the carriage transversely and a key to actuate the toggle joints.

19. In a front strike typewriter the combination of an endwise movable truck, a platen carriage linked to the truck for endwise movement therewith, means for moving the carriage rearward transversely on the 20 links out of the printing field, means for preventing the lifting of the carriage until the end of said rearward movement, means for lifting the carriage on the truck at the end of its said rearward movement, means for 25 locking the carriage against transverse movement while it is being lifted and means for locking the carriage on the truck in its said lifted position.

In testimony whereof I hereto affix my signature.

FREDERIC W. HILLARD.
